STRUCTURAL ASSEMBLIES

William M. Clelland, Westfield, N.J., Jack P. Wilson, Wynnewood, and Donald C. Glassford, Philadelphia, Pa., assignors to Proctor & Schwartz, Inc., Philadelphia, Pa., a corporation of Pennsylvania

Application July 29, 1954, Serial No. 446,583

1 Claim. (Cl. 72—14)

The present invention relates to new and novel improvements in structural assemblies for the housings and enclosures of industrial equipment, and more particularly to a novel composite concrete and lining assembly for ovens, silo towers, spray dryers and various other equipment.

Such structures as heretofore constructed, and particularly those of large size in the form of towers have been fabricated of heavy welded plate to withstand the forces due to wind loading in hurricane areas and the weight of machinery located high in the air. Thus the cost of material and labor in manufacturing are excessively high. For example, a stainless steel tower strong enough to support itself would be very expensive and involve a lot of welding, bracing and gussetting for strength and smooth joints.

One object of the present invention is to provide a composite tower formed by a housing of strong, relatively cheap material and a thin, smooth metal lining, such as stainless steel or other special metals.

Another object is to provide a concrete tower of sufficient strength to meet all requirements to resist wind forces and as a support for heavy machinery in association with an internal metal lining.

Another object is to provide a novel framework in combination with a concrete housing wherein none of the framework is exposed on the outside of the concrete wall.

Another object is to provide a metal framework housed between an internal metal lining and a concrete wall, such wall embedding a circumferential portion of the framework and forming a space with the lining for the other portion of the framework.

A further object is to provide a dryer assembly having a stainless steel lining for smoothness and cleanliness so necessary in pharmaceutical and food drying.

A further object is to provide a metal framework in combination with a concrete wall wherein an inner metal lining for the framework is insulated from the concrete wall.

A still further object is to provide a dryer formed of concrete and a metal framework wherein provision is made for free expansion of the framework.

These and other objects of the invention and the numerous features and details of the construction and assembly of the elements thereof, are hereinafter fully set forth and described with reference to the accompanying drawings, in which:

Fig. 1 is a plan view of a spray tower-dryer embodying the novel members and constructions of the invention, and here shown illustratively in the form of a cylinder;

Fig. 2 is a sectional view on line 2—2 of Fig. 1;

Fig. 3 is a fragmentary circumferential sectional view on an enlarged scale and taken in the horizontal plane of the junction of a vertical and a horizontal strut;

2

Fig. 4 is a fragmentary circumferential sectional view showing another form of structural member assembled according to the invention;

Fig. 5 is a fragmentary circumferential sectional view showing a modified structural assembly of the invention;

Fig. 6 is a perspective view of the junction between a vertical column strut and transverse strut members including an anchoring gusset;

Fig. 6a is a fragmentary elevational view of the disclosure in Fig. 6 showing the gusset in full lines;

Fig. 7 is a perspective detail view of the structural member shown in Fig. 4; and

Fig. 8 is a perspective view of a modified structural junction similar to that shown in Fig. 6.

Referring to the drawings and particularly Figs. 1 and 2, a tower structure is shown as generally comprising a concrete wall 10 housing a structural sheet metal framework 11 in such circumferential relation as to provide a heat insulating space 12, which in some instances can be filled with mat or other insulation. One form of structural member used to form the framework comprises two similar sections or lengths of rolled sheet metal secured together and having the required thickness or gauge to impart the necessary strength and rigidity

20 to the member. Referring to Figs. 3 and 6, each section of the member is in the form of a channel having walls 13 diverging from opposite sides of a base 14, and each wall terminating in a reversely bent end 15 spaced from its wall to form an auxiliary lengthwise channel 16. As 30 a complete structural member the two sections are united by welding or otherwise joining the bases 14 together in back-to-back relation, thus bringing the side channels 16 into juxtaposed relation with the ends 15 spaced apart, thereby forming a generally tubular head of generally 35 I-section having a slot running the length thereof. Structural members thus shaped are used as vertical columns 17 and horizontal stringers 18 joined together to form a framework such as shown in Fig. 2.

As shown in Figs. 6 and 6a the vertical and horizontal strut members are connected together by a gusset 20 so attached that the meeting ends of columns sections 17 are spaced one from another while the column straddling stringers 18 are spaced from the column. Thus the ends 40 of the column members terminate in a clearance or gap 21 and the respective ends of the stringers 18 terminate in clearances or gaps 22. These clearances 21 and 22 are filled with the concrete forming the outer wall and thus compensate for strut expansion within the limits 45 of the clearances provided. When the concrete wall has set each gusset 20 is preferably removed to relieve the members for free expansion, and to permit the installation of a metal lining as hereinafter set forth.

In Fig. 3 a section of the complete assembly is shown 50 wherein the gussets 20 have been removed and the inner metal lining 23 is in place. The lining 23 is formed by panel sections attached to the inner tubular head of the strut member with the joint between the panel sections closed by a snap-on strip 24. In pouring the concrete 55 a temporary wood spacer is positioned in contact with the outer face of the lining 23 to provide a circumferential space 25 for insulating purposes. This space may be filled with a suitable insulating material such as insulating concrete or may be left vacant as desired for 60 the particular installation. The concrete is poured between this wood spacer and an outer form, not shown. It will thus be seen that the novel assembly of the invention provides a framework in which a circumferential outer portion is embedded in concrete as a support while the inner circumferential portion supports the lining 23 in spaced relation from the concrete wall upon the removal of the inner concrete form spacer. An important

65 70 75 80 85 90 95

advantage of this assembly is that no metal of the framework is exposed on the outside of the wall 10.

In the form of the invention shown in Figs. 4 and 7, the strut member is a half length of the member shown in Fig. 3, and comprises a T-section having a lengthwise rib 26 and tubular head 27, split lengthwise by a slot 28, for association with the snap joint strip 24 as described. In this instance the rib 26 is provided with anchoring plates 30 welded to the rib 26 at spaced intervals and projecting from opposite sides to form a stable anchor when molded into the concrete an shown in Fig. 4. In this form of the invention the concrete wall 10 is poured between forms to provide an air gap space 31 with the lining 23. It is to be understood that the T-section can be used for either horizontal or vertical members in combination with full section members but, preferably, the construction will be full I-section verticals for strength and T-section bowed horizontal members for low cost.

In the form of the invention shown in Fig. 5 a strut member 32, like that shown in Fig. 3 is used, the outer or embedded head of which is anchored to wire mesh 33 used as a reinforcement for the concrete. This anchoring includes a strap nut 34 seated in the strut head and clamped in place by a bolt 35 passing through the strut slot and having its head bearing against a clamp plate 36. Thus the nut 34 and plate 36 clamp the strut and reinforcement together. As assembled the lining 23 is spaced from the wall 10 to provide an insulating air space. This latter may be filled with concrete, also for insulating purposes.

Constructions utilizing a combination of the I- and T-section structural members may also be employed as desired. Thus, in Fig. 8 of the drawings there is disclosed the junction of a structure in which the vertical columns consist of I-section structural members and the horizontal struts consist of T-section structural members. This is a preferred form of construction because the I-section vertical columns provide adequate strength to the structure while the T-section horizontal struts cost much less than the I-section members yet have sufficient strength to permit of their use in the structure as horizontal struts. Of course, the reverse of this arrangement, namely, a structure having T-shaped vertical columns and I-shaped horizontal struts can also be employed if found desirable in any particular case.

It will now be apparent that a complete, unitary structure has been devised wherein a housing of sufficient strength to meet all requirements in use is provided in association with a novel internal framework including a relatively thin, smooth metal lining. Thus a structure of concrete or other relatively cheap material provides the necessary strength and makes possible the use of steel or other metal as a lining at a reduced thickness because lining strength requirements are a minimum. The internal structure might be stainless steel, aluminum, or other type of special metal required for the purpose. In food drying, or pharmaceutical or biological drying a stainless steel lining is a necessity, and in some cases of chemical drying aluminum and copper may be a necessity along with stainless steel, and this invention makes such material possible by reason of reduced cost as compared

to the use of such materials normally required to meet strength conditions.

While particular embodiments of the present invention have been illustrated and described herein, it is not intended to limit the invention to such disclosure and changes and modifications may be made and incorporated therein within the scope of the following claim.

We claim:

10 A tank structure comprising; a generally cylindrical outer concrete wall, a plurality of parallel metal structural members extending longitudinally of the interior of said wall and constituting reinforcing and supporting columns extending longitudinally of said tank, said longitudinally extending structural members being spaced a predetermined distance apart, a plurality of arcuate metal structural members extending circumferentially of the interior of said wall and being positioned intermediate said longitudinally extending structural members and constituting stringers extending circumferentially of said tank, said arcuate structural members being of lesser extent than said predetermined distance between adjacent members of said longitudinally extending structural members to provide a clearance space between each end of said arcuate structural members and said longitudinally extending structural members to permit relatively free expansion of the members relative to one another, said longitudinally extending structural members and arcuate structural members having their outer portions interlockingly embedded in the concrete wall with their inner portions projecting from said wall inwardly of said tank a predetermined distance, the projecting portions of said longitudinally extending structural members and said arcuate structural members having spaced apart side walls terminating in spaced flange portions extending inwardly 20 toward each other, said side walls and flange portions defining there within a continuous shallow chamber extending the full length of each of said longitudinally extending structural members and arcuate structural members and the corresponding edge flanges of the members having 25 their free edges spaced apart to provide a continuous slot opening to each chamber, wall panel members interiorly of said tank overlying said longitudinally extending structural members and arcuate structural members and spaced thereby from said concrete wall a predetermined distance, 30 and means engaged with said panel members and projecting through said slots interiorly of the chambers in said longitudinally extending structural members to secure the panels thereto.
